United States Patent Office

Des. 213,381
Patented Feb. 25, 1969

213,381

BAR CABINET OR SIMILAR ARTICLE

Louis R. Clerico, 235 NE. 122nd St.,
North Miami, Fla. 33161

Filed Dec. 8, 1967, Ser. No. 9,707

Term of patent 14 years

U.S. Cl. D33—19
Int. Cl. D6—01

The side of the cabinet not shown is a mirror image of the side shown while the back of the cabinet is plain and conventionally flat.

I claim:

The ornamental design for a bar cabinet or similar article, substantially as shown and described.
